METHOD OF AND APPARATUS FOR APPLYING WALL FINISHES

Filed Nov. 9, 1929

UNITED STATES PATENT OFFICE

EDWARD J. MILLER, OF MILWAUKEE, WISCONSIN

METHOD OF AND APPARATUS FOR APPLYING WALL FINISHES

Application filed November 9, 1929. Serial No. 406,025.

This invention relates to certain new and useful improvements in wall finishes and refers more particularly to a method of applying a plastic material to resemble various types of stone and other similar surfaces.

It is an object of this invention to provide a conveniently handled tool with which plastic material may be pressed onto a supporting surface or wall, with its outer surface resembling stone or the like, quickly and efficiently.

Another object of this invention resides in the provision of a tool of the character described with which predetermined quantities or batches of plastic material may be individually forced onto a suitable backing or supporting surface and whereby a uniform thickness of the finishing surface is insured.

And a further object of this invention resides in the provision of means for preventing the adhesion of the plastic material to the tool during the removal of the tool and which remains on the formed material to prevent evaporation and permit more thorough dehydration.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is an elevational view of a portion of a wall formed in accordance with my invention;

Figure 2 is a cross sectional view taken through Figure 1 on the plane of the line 2-2;

Figure 3 is a perspective view of the tool for applying the material to obtain the desired finish;

Figure 4 is a transverse, sectional view taken through Figure 3 on the plane of the line 4-4 and illustrating the manner of applying the plastic material to metal lathe;

Figure 5 is a cross sectional view taken through Figure 4 on the plane of the line 5-5 with the tool in its retracted position preparatory to being withdrawn; and

Figure 6 is a view similar to Figure 2 illustrating the finishing material applied onto an undercoat of plaster or the like.

Referring now more particularly to the accompanying drawing, the numeral 5 represents a wall of conventional construction having metal or other suitable lath 6 onto which the exterior surface 7 of the wall is adapted to be applied. The surface 7 is formed of plastic material applied by means of a tool 8 which gives its outer surface a close resemblance to stone.

A finish of this type has heretofore been impossible, but is readily obtained by the use of a receptacle or casing 9 open at its front and having its rear wall 10 provided with an opening 11. The casing 9 is preferably formed of sheet metal and slidably receives a plunger 12 whose sides snugly engage the inner walls of the casing and whose outer surface is shaped to resemble roughly cut stone. The peripheral edges of the outer surface are projected to form beads 13 which serve to shape the plastic material to represent the mortar, between the stones in the completed wall.

A U shaped handle frame 14 is secured to the back of the plunger by screws 15 with its side arms extending through the opening 11 of the casing, the width of the frame being slightly less than the length of the opening so that the frame sides are directly adjacent the ends of the opening. The outermost ends of the frame sides mount a handle 16 by means of a bolt 17 fixed in the handle and extended through aligned apertures in the frame sides. Both ends of the bolt are apertured, as at 19, to slidably receive stop pins 20 which are adjustably secured against movement with respect to the bolt and the handle by nuts 18 threaded on the outer ends of the bolt.

Both ends of the bolt are apertured, as at 19, to slidably receive stop pins 20 which are adjustably secured against movement with respect to the bolt and the handle by nuts 18 threaded on the outer ends of the bolt.

As best illustrated in Figure 4, the inner ends of the pins 20 are adapted to engage the outer surface of the wall 10 to limit inward movement of the plunger. Outward movement of the plunger is adjustably limited by a pair of nuts 23 threaded on studs 21 slideable in apertures 22 formed in the wall 10 and secured to the plunger to be movable therewith.

- 10 In use, the plunger is retracted to its outermost position, illustrated in Figure 4, and a piece of waxed paper or other suitably flexible material 24 is placed within the casing to cover the outer uneven surface of the plunger. The casing outwardly of the plunger is then filled with plastic material 25 which consists principally of cement, or the like, and properly positioned with its open front against the metal lath of the wall.
- 15 The plunger 9 is then forced inwardly through the medium of the handle 16 until the stop pins 20, which have been adjusted to permit the desired degree of movement, engage the casing wall 10 and consequently limit further inward movement of the plunger. This movement of the plunger forces the plastic material onto the metal lath and at the same time places the material in the desired state of compression.
- 20 As the casing, which is in fact a mold, is individually filled, a pleasing color combination is obtainable by using different colors of plastic material.

25 The waxed paper or other suitable flexible material which covers the face of the plunger to prevent the adhesion of the material to the plunger is left on the surface of the pressed material to cover the completed wall. This causes the material to cure from the 30 inside and permits a more thorough dehydration of the same, thus producing a harder and more durable surface. The coating of waxed paper also serves to hold the plastic material against sagging from its own weight.

To remove the tool, the handle 16 and consequently the stop pins 20 are turned out of alignment with the handle frame sides, as illustrated in Figure 5, to enable the casing 35 to be withdrawn without affecting the position of the plunger. Maintaining the plunger in its position against the plastic material during the withdrawal of the casing, precludes the possibility of disturbing its formed 40 condition and greatly facilitates the removal of the tool. With the casing thus withdrawn, the plunger may be readily removed from the formed material by slightly tilting the same either upwardly or downwardly and to 45 prevent suction from retarding such movement of the plunger, a plurality of air bleeds 50 are formed therein, passage of plastic material through the air bleeds being prevented by the covering of wax paper.

55 It is noted that the studs 21 are provided

with heads 27 which engage the wall 10 and limit the outward movement of the casing and thus prevent its movement beyond the plunger. It is also apparent that the stop pins 20 by limiting the inward movement of the plunger insure a uniform density and thickness of the finishing material over the entire wall.

If desired, the finishing material may be applied, as illustrated in Figure 6, onto an 75 undercoat 28 of suitable material such as plaster or the like. Inasmuch as the material from which the finishing coat is formed is rich in cement it is comparatively expensive and, therefore, this method of application, 80 by permitting a relatively thinner layer of finishing material, considerably reduces the cost.

Where an undercoat is used, the stop pins 20 and the nuts 23, which limit inward and 85 outward movement, respectively, of the plunger, are adjusted so that the quantity of material received in the casing and the movement of the plunger is comparatively less than where the finishing material is applied 90 directly to the metal lath.

From the foregoing description taken in connection with the accompanying drawing, it will be readily apparent to those skilled in the art to which an invention of the character described appertains, that I provide a novel wall finish and a tool for applying the same which enables plastic material to be applied in a manner so as to closely resemble cut stone and other similar surfaces.

100 What I claim as my invention is:

1. The herein-described method of applying a surface finish which consists, in filling a receptacle with plastic material, and in forcing all of the material from the receptacle 105 onto the surface to form a section of covering conforming in size and shape to the receptacle.

2. The herein-described method of applying plastic material to a wall to resemble stone and the like which consists in pressing a quantity of plastic material from a receptacle onto a wall by means of a member whose surface is formed to represent the finish desired.

3. The herein-described method of applying plastic material to a wall to resemble stone and the like which consists in, pressing a quantity of the plastic material onto a suitable backing by means of a member whose surface is formed to resemble the finish desired, and in covering the surface of said member with flexible material to prevent adhesion of the plastic material to the member.

4. The herein-described method of applying plastic material to form a wall finish which consists, in covering a tool whose surface is formed to resemble the finish desired with relatively thin flexible material, in placing a quantity of plastic material on the flexible material, in pressing the plastic material onto 130

the wall, and leaving the flexible material on the pressed surface.

5. The herein-described method of applying a surface finish to represent stone or the like, which consists in pressing individual quantities of plastic material onto the surface in juxtaposition to entirely cover the surface from a receptacle adapted to hold said quantities of plastic material.

10. The herein-described method of applying a surface finish to represent stone or the like, which consists in pressing individual quantities of plastic material onto the surface in juxtaposition to entirely cover the surface by forcing a member having a surface formed to represent the finish desired and covered with the plastic material, against the surface with a single motion substantially perpendicular to the surface.

20. The herein-described method of applying a surface finish to represent stone or the like, which consists in pressing individual quantities of plastic material onto the surface in juxtaposition to entirely cover the surface by means of a member whose surface is formed to represent the finish desired and in simultaneously applying a covering to the exterior of the individual quantities of plastic material as they are pressed into position to prevent too rapid dehydration thereof.

25. The herein-described method of applying a surface finish which consists in filling a receptacle with plastic material, in forcing the contents of the receptacle onto the surface to cover a portion thereof, holding the receptacle stationary against the surface while material is forced therefrom so that the entire contents of the receptacle are applied at one place to cover an area substantially co-extensive with the receptacle, in refilling the receptacle with plastic material and in forcing the contents of the receptacle onto the surface to cover an area immediately adjacent the previously covered portion of said surface.

30. The herein-described method of applying a surface finish which consists in filling an open sided receptacle with plastic material, placing the receptacle open side against the surface, pressing the plastic material against the surface by means of a member whose surface is formed to resemble the finish desired while maintaining the receptacle against the surface, in withdrawing the receptacle from the pressed material while holding the member against the same, and in removing the member after the receptacle is withdrawn.

35. A tool for applying plastic material to a wall surface comprising a casing having an open front and adapted to hold the quantity of plastic material, a plunger movable within the casing to press the plastic material onto the wall, handle means for moving the plunger, and means carried by the handle means

for limiting the movement of the plunger to regulate the degree of pressure to which the plastic material is subjected and its thickness on the wall.

40. A tool for applying plastic material to a surface, comprising a casing having an open front and adapted to hold a quantity of plastic material, a plunger movable within the casing, a handle for moving the plunger to press the plastic material onto the surface, means carried by the handle and engageable with the casing to limit the movement of the plunger in pressing the material onto the surface to regulate the degree of compression to which the material is subjected and its thickness on the surface, and means movably mounting the handle whereby the limiting means is readily movable out of operative position to enable the casing to be withdrawn from the pressed material while the plunger is retained thereagainst.

45. A tool for applying plastic material to a wall comprising a casing having an open front and adapted to hold a quantity of plastic material, a plunger movable within the casing, a handle for moving the plunger outwardly of the casing to press the plastic material therein onto the wall, means carried by the plunger projecting through the closed back of the receptacle to freely rotatably mount the handle, and means connected with the handle and engageable with the receptacle closed rear wall to limit the outward movement of the plunger by the handle and regulate the degree of compression to which the plastic material is subjected and its thickness on the wall, said limiting means being movable with the handle to enable the same to be readily moved out of operative position to permit the casing to be withdrawn from the pressed material on the wall while the plunger is retained thereagainst.

In testimony whereof I have hereunto affixed my signature.
